UNITED STATES PATENT OFFICE.

SAMUEL SEVERSON, OF VALDERS, WISCONSIN.

LUBRICATING SYSTEM FOR INTERNAL-COMBUSTION ENGINES.

1,404,797.

Specification of Letters Patent. Patented Jan. 31, 1922.

Application filed May 18, 1920. Serial No. 382,235.

To all whom it may concern:

Be it known that I, SAMUEL SEVERSON, a citizen of the United States, and resident of Valders, in the county of Manitowoc and 5 State of Wisconsin, have invented certain new and useful Improvements in Lubricating Systems for Internal-Combustion Engines; and I do hereby declare that the following is a full, clear, and exact description 10 thereof.

My invention relates to new and useful improvements in internal combustion engines, and pertains particularly to means for lubricating the same.

15 The principal object of the invention is to provide a simple, efficient and inexpensive lubricating system for use on different types of internal combustion engines, but especially on those working on the two cycle 20 principle.

Still another object of the invention is to provide a gravity feed lubricating system which will positively and thoroughly lubricate all of the main working parts of an engine.

25 With these general objects in view the invention resides in the novel features of construction, combination and arrangement of parts which will be hereinafter more particularly described and claimed.

In the accompanying drawings:

Figure 1 represents a vertical longitudinal sectional view through a conventional form of a two cycle engine having my improved lubricating system applied thereto.

Figure 2 is a horizontal transverse section taken substantially on the plane of the line 2—2 of Figure 4.

40 Figures 3 and 4 are detail vertical sections taken substantially on the plane of the lines 3—3 and 4—4 of Figure 2.

Referring more particularly to these drawings, it will be seen that the reference character 1 denotes the cylinder of an internal 45 combustion engine, for instance an engine of the two cycle type mounted upon a crank casing 2 and having a piston 3 reciprocable therein. This conventional structure also includes a crank shaft 4 having a crank 5 and connected through said crank pin and 50 a connecting rod 6 with the piston 3. In most two cycle engines as now constructed, it is necessary to have oil in the crank case, to mix oil with the fuel or to use other or more 55 complicated systems.

In the present embodiment of the inven-

tion a hollow wrist pin 7 is used for mounting the piston 3 on the end of the connecting rod 6 and one end of the pin is preferably closed as at 8 and the other end open, the 60 open end, however, being of a diameter considerably smaller than the inner diameter of the pin 7 as indicated at 9. Also the piston wall adjacent the open end of the wrist pin 7 is provided with a longitudinally extending groove or channel 10 for the reception of a cover plate 11 in the form of an elongated bearing strip.

The cylinder wall 1 adjacent the inner end thereof is provided with an opening 12 70 which communicates with a gravity feed lubricating fluid cup 13. This cup may be of any desired type and is supported on the outside of the wall of the cylinder as is customary in mounting such devices. 75

The purpose of the cover plate 11 is to extend over this inlet opening 12 and to keep it closed at all times except when the movement of the piston 3 brings the axis of the wrist-pin 7 into alignment therewith. 80 When this occurs oil may flow from the cup 13 and through the inlet opening 12 into the hollow wrist-pin through a hole 14 in said plate, said hole being in alignment with the axis of said pin. Consequently 85 since the inlet opening 12 and the hole 14 are only intermittently aligned, it is necessary that the cover plate 11 extend inwardly of the interior edge of the piston 3 as shown in Figure 1. 90

A leaf spring of suitable design is located in the channel 10 between the bottom thereof and the adjacent surface of the cover plate 11 so as to continuously urge the latter outwardly into contact with the cylinder 95 wall. Therefore in order to cause oil to flow directly into the wrist-pin 7 from the hole 14, the latter is surrounded by a sleeve 16. This sleeve has an exterior diameter substantially equal to the diameter of the open 100 end of the wrist-pin and is slidable there-through upon movement of the cover plate 11. As indicated at 17 the wall of the opening 14 adjacent the outer face of the cover plate 11 is converged so that a sharp edge 105 is formed.

The hollow wrist-pin thus provides an oil reservoir from which lubricating fluid may be distributed to various necessary parts of the engine. In the present instance oil 110 ducts 18 and 19 extend from the wrist-pin 7 adjacent the open and closed ends respec-

tively thereof to an annular oil groove 20 formed in the piston wall. The piston is thus readily lubricated, whereas the wrist-pin bearings and the crank pin bearing are 5 lubricated by fluid which flows from the oil reservoir through intermediately located ducts 21. One of these ducts communicates with a passageway 22 in the connecting rod 6, the same extending from the wrist-pin 10 bearing to the crank pin bearing. Inasmuch as the level of the oil in the wrist-pin adjacent the open end thereof will be at a higher level than at the closed end, owing to the viscosity of the oil and the relatively slow 15 speed with which it enters, the wrist-pin openings of the ducts 18, 19 and 21 are disposed at different levels. In other words the openings of the ducts 18, 19 and 21 are in progressively lower planes from the open 20 end of the wrist-pin toward the closed end thereof. By such an arrangement similar quantities of oil may flow through the several ducts regardless of their location with respect to the incoming oil.

25 From the foregoing description taken in connection with the accompanying drawings, it will be obvious that I have invented a very simple lubricating system which will be very efficient in operation and still is 30 quite economical. That is to say all of the principal and important working parts of an engine, such as the piston and cylinder walls and wrist-pin and crank pin bearings 35 may be lubricated through a supply of oil in a single oil cup located exteriorly of the engine cylinder. However, should it be necessary other parts of the engine might well be lubricated from the supply located in the oil reservoir formed within the hollow 40 wrist-pin. Consequently various changes may be made in the form and proportion of the different parts of the apparatus without departing from the principles of the invention or sacrificing any of the advantages.

45 I claim:

1. In an engine lubricating system, a cylinder, a piston reciprocable therein and hav-

ing a fluid passage through its wall, a lubricating fluid supply opening through the cylinder wall and adapted to have said fluid passage intermittently aligned therewith, an elongated plate carried by the piston longitudinally thereof for covering the supply opening, said plate having a hole to be 55 aligned with the supply opening, means urging the plate toward the cylinder wall, and a sleeve extending laterally from the plate and surrounding said hole, said sleeve being 60 slidable in said piston wall passage.

2. In an engine lubricating system, a cylinder, a piston reciprocable therein and having a hollow wrist-pin, one end of said wrist-pin being open, a lubricating fluid supply opening through the cylinder wall 65 adapted to have the open end of the wrist-pin intermittently aligned therewith, and lubricating fluid ducts extending from the pin to parts to be lubricated, the wrist-pin ends of said ducts being in successively 70 lower planes from the said open end of the pin toward the opposite end.

3. In an engine lubricating system, a cylinder, a piston reciprocable therein and having a hollow wrist-pin, a lubricating fluid 75 passage through the piston wall in alignment with the wrist-pin and having communication with the interior thereof, a lubricating fluid supply opening through the cylinder wall, and adapted to have said fluid 80 passage intermittently aligned therewith when the engine is in operation, an elongated plate carried by the piston and extending from the fluid passage longitudinally towards the crank shaft and covering 85 the supply opening when the piston is moved inwardly beyond the same, and means urging said plate towards the cylinder wall, said means being exerted throughout the length of the plate.

90 In testimony that I claim the foregoing I have hereunto set my hand at Valders, in the county of Manitowoc and State of Wisconsin.

SAMUEL SEVERSON.
